UNITED STATES PATENT OFFICE.

THOMAS SPENCER MILLER, OF SOUTH ORANGE, AND JOSEPH H. DICKINSON, OF MONTCLAIR, NEW JERSEY.

SHEAVE-BLOCK.

No. 837,703.

Specification of Letters Patent.

Patented Dec. 4, 1906.

Application filed June 27, 1905. Serial No. 267,173.

To all whom it may concern:

Be it known that we, THOMAS SPENCER MILLER, a resident of South Orange, and JOSEPH H. DICKINSON, a resident of Montclair, in the county of Essex and State of New Jersey, citizens of the United States, have invented certain new and useful Improvements in Sheave-Blocks, of which the following is a specification.

Our invention relates to certain novel and useful improvements in sheave-blocks, and is particularly applicable to an appliance of the class described adapted to be employed in connection with skidding apparatus.

In carrying out the present invention it is our purpose to provide a sheave-block which will embody the desirable features of simplicity and durability of construction and convenience in operation and use.

Our invention consists in the construction, combination, and arrangement of parts set forth in and falling within the scope of the appended claims.

In the accompanying drawings like characters of reference indicate like parts in all the views.

Figure 1 is a vertical sectional view taken through a block on approximately the line $x-x$ of Fig. 2. Fig. 2 is a transverse vertical section view of a block embodying our improvements. Fig. 3 is a detail view of the sheave-bolt, and Fig. 4 is a similar view of the inner bushing surrounding the bolt. Fig. 5 is a view of our improved block in end elevation.

Referring now to the accompanying drawings in detail, A A indicate the sides of the block. These sides are preferably formed of malleable iron and are connected at their upper and lower end portions through the medium of the securing-bolts 5.

6 indicates the swivel-eye of the block, having at its end portion an enlarged head 7, fitting in the grooved parts 8 at the top of the block and bearing against the shoulders formed by such groove, so that it is impossible for the eye to be disconnected when the sides are properly bolted and fastened together. The construction and formation of the interior faces of these sides form an important feature of the invention, inasmuch as we so construct the inner faces of the side members that the sheave-wheel, which is, as hereinafter described, of relatively greater

cross-diameter at its center than at its periphery, may be inserted in position, without taking the entire block to pieces.

As will be seen particularly by reference to Fig. 2, each side member is formed with a hole 9 for the passage of the main bolt 10, which bolt supports the sheave 11. The portion of each face surrounding the bolt-hole is concave or cut away, as at 12, to form a depression or recess to accommodate the widened portion 12 of the sheave. The upper portion of each interior side is also grooved or depressed, as at 13, to accommodate the head 6 of the swivel-eye and the upper run of the rope. The sheave 11, as will be seen by reference to Fig. 2, is formed with a grooved periphery 14, which is of relatively less cross-diameter than the large central portion of the sheave, and the connecting-web 15 is lightened by cutting away the metal thereof, as at 16. The enlarged or widened central portion 17 of the sheave is formed by inclined side members 18, making a central chamber 19, in which is adapted to be placed a lubricating material.

19 is the screw-plug for the oil-hole 20, through which any suitable lubricant may be introduced to the chamber. Passing centrally through the hub of the sheave is the copper bushing 21, made fast with such hub portion by the securing-screw 22, and such hub is provided with a plurality of openings 23 to permit the lubricant to flow from the chamber to the steel bushing 24, fast with the main bolt or pin 10. This inner or steel bushing 24 is held against movement by means of the key 25, projecting from the shank of the bolt, and while the latter in turn is held against movement relative to the sides of the block by means of a second key projection 26, adapted to enter a small groove in such block. Thus it will be observed when the block is in use the sheave thereof with its copper bushing is designed to turn upon the steel sleeve or bushing fast with the pin, and consequently immovable relative to the main portion of the block. The pin or bolt 10 is provided with an ordinary nut 10', through the medium of which it is held securely in position.

By reference to Fig. 2 it will be seen that the inner or steel bushing is of relatively greater length than the outer or copper bushing. The steel bushing thus performs the

office of a spacer for the sides of the block, and at the same time the copper bushing, having sufficient room endwise, may rotate easily and freely.

- 5 When it is desired to insert the sheave-wheel, it is not necessary to dismantle or take apart the block-frame, for, as will be seen in Fig. 5, the wheel may easily be slipped in from the side, the recesses on the interior faces accom-
10 modating the widened central or hub portions of such wheel. After such insertion the bolt 10 may be put in position and the nut 10' threaded on the end thereof. Likewise to remove the sheave it is only necessary to
15 take out the bolt 10, when the sheave-wheel may be easily withdrawn.

From the above description, taken in connection with the accompanying drawings, the manner of constructing our improved 20 sheave-block will be readily understood by those skilled in the art to which it pertains and its many advantages appreciated. By having the hub of the sheave formed with a bronze bushing working upon the steel bush-
25 ing of the center pin we are enabled to obtain an easy-running sheave which is also self-oiled.

Having thus described our invention, what we claim, and desire to secure by Letters 30 Patent, is—

1. A sheave-block recessed on the interior faces of the side members thereof, a sheave formed with a relatively widened central portion adapted to lie within the recessed portions of the interior faces, and a bolt passing through the faces and through the sheave.

2. A sheave-block comprising side members recessed on their interior faces, and a sheave-wheel having a widened chambered 40 central portion adapted to fit within the recessed portions of the side members.

3. A sheave-block comprising side members recessed on their interior faces, each of such faces having a groove therein to permit 45 the passage of a rope, and a sheave-block formed with a widened central portion adapted to lie within the recesses of the face.

4. A sheave-block comprising a frame formed of side members, a sheave-wheel, a bolt passing through said side members and sheave-wheel, a sleeve or bushing fast with 50 said bolt, a second bushing passing through the hub of the sheave-wheel and fast therewith and adapted to bear upon the bushing of the bolt, the latter bushing being longer than the bushing of the sheave.

5. A sheave-block comprising a sheave, a frame for said sheave formed of side members having recesses or depressions on the interior faces thereof to accommodate the central portion of the sheave, such sheave having a widened central chambered portion adapted 55 to receive lubricating material.

6. A sheave-block comprising a sheave-

wheel, a frame formed of side members with-
in which the wheel is mounted, a bolt securing the wheel within the frame, a relatively long bushing surrounding said bolt, and a second relatively short bushing of relatively softer material than the first-mentioned bushing fast with the sheave-wheel and adapted to bear against the first-mentioned bushing or sleeve.

7. A sheave-block comprising a frame formed of side members, a sheave-wheel mounted therein, a bolt passing through said frame and sheave-wheel, a bushing extending through the hub portion of the wheel, and a relatively longer bushing surrounding the bolt against which the bushing of the sheave-wheel is adapted to bear.

8. The combination of a frame formed of a plurality of side members having recesses on the interior faces thereof, a sheave-wheel formed with a widened hub or central portion adapted to lie within the recessed portions of the side members, a bolt securing the sheave-wheel within the frame, a bushing or sleeve passing through the central portion of the sheave-wheel, and a relatively longer bushing or sleeve surrounding the bolt and against which the bushing of the sheave is adapted to turn.

9. The combination of a frame formed of side members, a sheave-wheel mounted therein, a bolt passing through said frame and sheave-wheel, a bushing for said sheave-wheel and a relatively longer bushing or sleeve surrounding the bolt.

10. In a sheave-block, a frame, and a sheave-wheel rotatably mounted in the frame, such wheel having a relatively widened central portion.

11. In a sheave-block, a frame and a sheave-wheel rotatably mounted in the frame, said wheel having a relatively widened chambered portion.

12. A sheave-block comprising side members recessed on their interior faces, a sheave-wheel formed with a widened central chambered portion adapted to lie within the recesses of the faces, a bolt passing through the bases and the sheave-wheel, a bushing surrounding said bolt, and a second bushing connected to the sheave-wheel and bearing against the first-mentioned bolt and having an aperture therein through which a lubricating material may pass from the chambered portion through to the bushing surrounding the bolt.

In testimony whereof we have signed our names to this specification in the presence of two subscribing witnesses.
